CLAIM

The ornamental design for a medical garment, as shown and described.

DESCRIPTION

FIG. 1 is a front perspective view of a new design for a medical garment.

FIG. 2 is a front view of a design of FIG. 1.

FIG. 3 is a rear side view of the design of FIG. 1.

FIG. 4 is a right side view of the design of FIG. 1.

FIG. 5 is a left side view of the design of FIG. 1.

FIG. 6 is a top view of the design of FIG. 1.

FIG. 7 is a bottom view of the design of FIG. 1; and,

FIG. 8 is a top perspective view showing the design in use. The broken lines represent portions of the medical garment that form no part of the claimed design.

1 Claim, 8 Drawing Sheets
